UNITED STATES PATENT OFFICE.

WARREN E. BEADLE, OF WISCONSIN RAPIDS, WISCONSIN.

PROCESS AND APPARATUS FOR REGULATING PAPER STOCK AND THE LIKE.

Application filed December 14, 1922. Serial No. 606,917.

To all whom it may concern:

Be it known that I, WARREN E. BEADLE, a citizen of the United States, residing at Wisconsin Rapids, in the county of Wood 5 and State of Wisconsin, have invented new and useful Improvements in Processes and Apparatus for Regulating Paper Stock and the like, of which the following is a specification.

10 My invention relates to a process and apparatus for automatically regulating the consistency or the per cent of solid matter contained in a flowing liquid, the invention being particularly adapted for use in paper 15 mills for regulating the consistency of paper stock, pulp or the like.

It is important, in the manufacture of paper and other articles from pulp, that the materials, while they are being carried 20 through the process of manufacture, should be of uniform consistency in order to obtain a uniform product.

The object of the present invention is to provide a simple device for regulating the 25 amount of water introduced into the mixture, which will be quickly responsive to variations in the consistency thereof, and positive and accurate in its operation.

The invention will be described in connection with the accompanying drawing 30 which illustrates one way in which the principles of my invention may be embodied.

In the drawing:—

Fig. 1 is a view partly in section and partly in elevation of a regulating means having 35 my invention applied thereto.

Fig. 2 is a plan view of the same.

Fig. 3 is a detail view illustrating the 40 operation of the invention.

Referring more particularly to the drawing, 5 designates a chest or vat which may contain paper pulp or stock, and which has a discharge pipe 6 leading from the lower portion thereof, which is provided with the usual pump 7 for propelling the pulp or stock to a point of utilization. During the 45 passage of the liquid through the pipe 6, a certain amount of water may be introduced into the same through a pipe 8 which is provided with a valve 9 for controlling the amount of water according to the consistency of the liquid. This valve is provided with a screw-threaded stem 10 which is rotated in one direction or the other to open

or close the valve. For effecting this rotation, the stem 10 carries a ratchet wheel 11 that is provided on its opposite faces with oppositely-directed teeth 12 and 13 which may be engaged by a pawl 14 having a pair of arms 15 and 16 extending on opposite sides of the ratchet wheel and selectively engageable with the teeth 12 and 13 to rotate the stem 10 in either direction. The pawl 14 is constantly reciprocated by means of a pitman 17 connected with a crank 60 disk 18 which is mounted on a shaft 19 and rotated by means of a wheel 20 driven from a motor 21.

It will be understood that when the pawl is swung to the left into the position shown 70 in Fig. 1, the stem will be rotated to the left or in an anti-clockwise direction to open the valve and admit more water to the mixture. If the pawl is swung to the right so as to engage the teeth 13, the rod 75 10 will be rotated in a clockwise direction to close the valve. If the pawl is held in its intermediate or neutral position, the same will be reciprocated without engaging either side of the ratchet wheel, and the valve will 80 remain in the position in which it is set.

For the purpose of shifting the pawl 14, one arm thereof is connected by a link 22, with a crank arm 23 which is secured to a shaft 24, one end of the shaft preferably 85 having secured thereto a cross arm 25 carrying one or more adjustable counterweights 26 and 27 which may be adjusted for varying the normal or neutral position of the regulator. Secured also to the 90 shaft 24 is a depending arm 28 having a paddle 29 secured to the lower end thereof, whereby a force applied to the paddle will rock the shaft 24 and shift the pawl 14 in proportion to the amount of force so 95 applied.

For the purpose of actuating the paddle 29 automatically, according to the consistency of the liquid, all or a portion of the flow of liquid is directed through an opening 30, or by other suitable means, into a chamber 31 which overflows the side 32 into another chamber 33, thence through an outlet 34, through which it is carried to a point of utilization, or back into the vat 5, as may 100 be desired. Thus, the liquid in the chamber 31 is always maintained at a constant level. The chamber is provided, near the bottom 105

thereof, with a small outlet 35 extending in the direction of the paddle 29, and preferably at an upwardly-inclined angle. Thus, the stream of liquid passing through the 5 constricted outlet 35 will be forced against the paddle 29 and will swing the same laterally to a certain extent to control the operation of the pawl 14. The liquid which is discharged through the outlet 35 will fall to 10 the bottom of the chamber 36, whence it may be discharged through a suitable opening 37 into the chamber 33, where it again commingles with the main stream of liquid and is discharged through the outlet 34.

15 The operation of my improved regulator will be best understood in connection with Fig. 3. Since the liquid in the chamber 31 is maintained at constant level, the inertia of the liquid discharged through the constricted outlet 35, which varies directly with the velocity of discharge, will vary inversely with the consistency or percentage of solid matter contained in the liquid. If the liquid is comparatively thick, the inertia 20 will be small and the impact against the paddle 29 will have little force, and consequently the paddle will remain in substantially the position shown in full lines in Fig. 3, and the ratchet 14 will be held in 25 the position shown in Fig. 1, whereupon the valve 9 will be opened to introduce more water into the mixture. When the liquid reaches the proper consistency, for which the regulating device has been adjusted by 30 means of counterweights 26 and 27, the impact will force the paddle to the position indicated at *a* in Fig. 3, whereupon the pawl 14 will be moved to neutral position and the valve 9 will remain as adjusted. If the 35 mixture tends to become too thin, the velocity of discharge from the outlet 35 will increase, thereby increasing the force of the impact against the paddle 29 and moving the latter to the position shown at *b* in Fig. 40. This movement will cause the pawl 14 to engage with the teeth 13 and the rod 10 will be rotated to close the valve 9.

45 From the foregoing description, it will be seen that the construction by means of which the principles of my invention may be carried out is very simple in its nature and easily installed, and is instantly responsive to variations in the consistency of the liquid, and positive in its operation. While 50 I have shown and described the specific structure of one form in which the invention may be embodied, it will be readily seen by those skilled in the art to which it appertains, that various modifications may be 55 made therein within the scope of what is claimed, without departing from the principles of the invention. Although I have described its use in connection with paper stock or pulp, it will be understood that the 60 invention may also be used with other

liquids in which the consistency depends upon solid particles in suspension or in solution.

What is claimed is:—

1. An apparatus for regulating the consistency of a flowing liquid comprising a valve for controlling the admission of water thereto, means for actuating the valve to vary the rate of flow of the water, and means for diverting a continuous stream 70 from said liquid and causing said stream to strike said actuating means, causing an impact thereagainst which serves to control the position of the valve, the force of said impact varying inversely with the consistency of said liquid.

2. An apparatus for regulating the consistency of a flowing liquid comprising a valve for controlling the admission of water thereto, a paddle mounted for oscillation 85 about a horizontal axis, means controlled by the position of said paddle for varying the position of the valve, a chamber through which the liquid passes and having a restricted outlet below the surface of the 90 liquid, said restricted outlet being in such a position as to direct the stream of liquid emitted therefrom against the paddle, so that the impact thereof serves to control the position of the paddle.

3. An apparatus for regulating the consistency of a flowing liquid comprising a valve for controlling the admission of water thereto, means rotatable in one direction to open the valve and rotatable in the other direction to close the same, means including a rock shaft for controlling the rotation of said rotatable shaft, a paddle secured to and depending from the rock shaft, and means for directing a constant stream of said 100 liquid against the paddle with a force varying inversely with the consistency of the liquid.

4. An apparatus for regulating the consistency of a flowing liquid comprising a valve for controlling the admission of water thereto, means rotatable in one direction to open the valve and rotatable in the other direction to close the same, means including a rock shaft for controlling the rotation of said rotatable shaft, a paddle secured to and depending from the rock shaft, a chamber in which a portion of the flowing liquid is maintained at a constant level, and a constricted outlet provided with a nipple inclined upwardly toward the paddle for directing the liquid from said chamber against the paddle, whereby the inertia of the discharge and the consequent force of the impact against the paddle varies inversely 110 with the consistency of the liquid.

5. An apparatus for regulating the consistency of a flowing liquid comprising a valve for controlling the admission of water thereto, means rotatable in one direction 115

to open the valve and rotatable in the other direction to close the same, means including a rock shaft for controlling the rotation of said rotatable shaft, a paddle secured to

ing a constant stream of said liquid against the paddle with a force varying inversely with the consistency of the liquid. 10

In testimony that I claim the foregoing as my own, I have hereto affixed my signature.

WARREN E. BEADLE.
